Filed July 17, 1963, Ser. No. 295,743
 8 Claims. (Cl. 307—88.5)

This invention applies in general to bistable triggers and more particularly to an improvement in Schmitt triggers which will permit designing a symmetrically firing Schmitt trigger.

Schmitt triggers, which are fast switching bistable triggers, are well known in the art. Their attributes and deficiencies have been frequently discussed in the literature. Probably the major problem in using a Schmitt trigger is the problem to which this invention is addressed. That problem resides in the fact that the critical voltage at which a Schmitt trigger will fire, in one direction, as the input signal to the trigger is increasing is different than the critical voltage at which that trigger will refire as the input signal is decreasing.

It is a major purpose of this invention to provide an improvement to the Schmitt trigger so that the voltage at which triggering occurs on the ascending slope of an input signal will be the same as the voltage at which triggering occurs on the descending slope of an input signal.

The difference in firing voltage at which the Schmitt trigger fires and refires is known as hysteresis. It is widely recognized that hysteresis is desirable in order to provide stability of switching and in order to speed up the rate at which switching occurs. Since the Schmitt trigger is designed for fast, stable switching, the loss of hysteresis is most undesirable.

Accordingly, it is a more specific purpose of this invention to provide a compensation for hysteresis that will result in symmetrical triggering without doing away with the hysteresis so that stability of operation and fast switching can be coupled with symmetrical triggering.

Prior art designs which are provided for symmetrical triggering have done so by eliminating the hysteresis and thus have resulted in circuits of limited stability. Before this invention, it had been presumed that hysteresis and symmetrical firing were conflicting characteristics. This invention teaches a technique whereby one may design to obtain both hysteresis and symmetrical firing.

Broadly and briefly speaking, the design technique taught by this invention involves a means for shifting the voltage level of the hysteresis after switching has occurred by an amount equal to the hysteresis. Thus full advantage is taken of the hysteresis effect to assure fast and stable switching. Then after the switching has been completed, the biasing level in the trigger is shifted by an amount that compensates for the hysteresis and permits refiring at the same voltage level as the firing level.

Other objects and purposes of this invention will become apparent from a consideration of the following detailed description and drawings, in which:

FIG. 1 is an electrical schematic of a transistorized prior art Schmitt trigger, and

FIG. 2 is an electrical schematic of a Schmitt trigger incorporating one embodiment of the improvement taught by this invention.

Concerning terminology

Throughout this application, it should be understood that a reference to an increase in voltage or a decrease in voltage does not refer to absolute magnitude but takes into account the sign of the voltage involved. Thus a change in potential from minus 12 volts to zero volts would be considered an increase in voltage. If this volt-

age were applied to the base of a transistor, it might be referred to herein as an increase in bias. Consistent with this terminology, when it is said herein that a decrease in potential on the collector of the transistor Q_1 results in pulling down the base of the transistor Q_2 , it is meant that the base of the transistor Q_2 goes from a more positive to a less positive value. To say that the base of the transistor Q_2 goes from a more positive to a less positive value may include passing through ground as when going from a positive value to a negative value. Indeed, consistent with this invention, a point that goes from let us say minus two volts to let us say minus 10 volts would be considered as going from a more positive to a less positive value.

Reference is made throughout this application to a Schmitt trigger because that term has achieved widespread use and covers a fairly clear cut class of trigger designs. However, it should be understood that this invention has applicability to any bistable switching circuit which exhibits the hysteresis characteristic above described.

The prior art

FIG. 1 illustrates a typical Schmitt trigger without the improvement added by this invention. The Schmitt trigger shown happens to involve two NPN transistors Q_1 and Q_2 .

The Schmitt trigger is a binary circuit having two states, in one state the transistor Q_1 is on and the transistor Q_2 is off; while in the other state the transistor Q_2 is on and the transistor Q_1 is off. The Schmitt trigger has the distinction over other binary circuits of having a very fast switching action, that is a very short switching time. The tying of the two emitters together and the provision of a common emitter resistor R_5 provides the additional regenerative feedback which speeds up the switching action. Since the operation of the Schmitt trigger is well known to those skilled in this art, it will not be necessary to do more than outline its operation to set the base for a discussion of the improvement provided by this invention. A more comprehensive discussion of the operation of the Schmitt trigger may be had by reference to paragraphs 5-10 and 5-11 in "Pulse and Digital Circuits" by Millman and Taub (McGraw-Hill, 1956). The Millman and Taub reference discusses the operation of the Schmitt trigger when designed to employ electron tubes instead of transistors. A short explanation of a transistorized Schmitt trigger is provided in paragraph 196 in "Basic Theory and Application of Transistors" (Army Technical Manual TM11-690, 1959).

Suffice it to say here, that the resistors R_{12} and R_{67} operate as a voltage divider to provide a control voltage on the base of the transistor Q_2 . The trigger of FIG. 1 is designed so that when in a quiescent state (that is there being no input signal E_s) the transistor Q_1 will be shut off because its base is connected to the negative supply B^- through the resistor R_1 . Under these conditions the transistor Q_2 will conduct since its emitter is negative, being connected to the negative supply B^- through the resistor R_5 , and its base is sufficiently positive relative to its emitter because of the selection of appropriate values for the voltage divider resistors R_{12} and R_{67} .

In the design illustrated herein (with the resistor and power supply values indicated in the figures), the base of the transistor Q_2 will be at approximately zero potential when transistor Q_1 is cut off. Since transistor Q_2 is conducting, its emitter will follow its base and the emitter current will be whatever is required to provide the required drop across the emitter resistor R_5 . The design is such that the emitter current required will assure conduction in the saturation portion of the Q_2 characteristic. In brief, Q_2 is hard on.

The input signal E_s when applied to the base of the transistor Q_1 will turn on that transistor Q_1 at the moment when the signal E_s becomes sufficiently positive to provide the forward bias necessary to cause the transistor Q_1 to start conducting.

As the transistor Q_1 turns on in response to the appropriately positive signal on its base, current through the resistor R_{43} will increase thereby causing a drop in potential at the collector of the transistor Q_1 , which drop in potential will be reflected in a proportionate drop in potential at the base of the transistor Q_2 . The proportionate voltage drop at the base of the transistor Q_2 is a function of the ratio between the voltage divider resistors R_{12} and R_{67} . Thus as the potential on the base of Q_2 goes negative there is a tendency for the transistor Q_2 to turn off.

To speed up the switching there is included in the Schmitt trigger type of design a connection between the emitter of the transistor Q_1 and the emitter of the transistor Q_2 which connection is then connected to the negative supply B^- through the resistor R_5 . As the transistor Q_1 turns on, the increased current through the resistor R_5 results in a less negative emitter potential (on both the emitters of the transistors Q_1 and the emitter of the transistor Q_2). Thus the flow of current through the transistor Q_1 , as that transistor turns on, simultaneously reduces the voltage on the base of the transistor Q_2 and increases the potential on the emitter of the transistor Q_2 . In this fashion the time it takes to turn off the transistor Q_2 is relatively small and the switching can be considered to be relatively fast as compared to other bistable designs.

The resistor values, voltages and designs are such that the transistors are turned hard on and hard off so that they operate in their saturation region and the magnitude of transistor current is substantially independent of the magnitude or rise time of the input signal E_s .

When the input signal E_s decreases in voltage magnitude below a certain critical point, this bistable trigger will switch back the other way. As the input signal E_s decreases, the base of the transistor Q_1 is rendered sufficiently negative by the negative supply B^- so as to turn the transistor Q_1 off. As it starts to turn off, a decrease in current through the transistor Q_1 will result in less current through the resistor R_{43} so that the collector of the transistor Q_1 will go more positive and, accordingly, a proportionate increase in potential will be applied to the base of the transistor Q_2 . Concurrently, the decrease in current through the common emitter resistor R_5 will drop the potential on the emitters therefore increasing the forward bias on the transistor Q_2 and increasing the rate at which the transistor Q_2 will turn on.

This Schmitt trigger, as does all Schmitt triggers, exhibits the well known Schmitt trigger phenomenon that is called hysteresis. This means that the magnitude of the critical signal voltage to trigger the transistor Q_1 on is greater than the magnitude of the critical voltage necessary to switch the transistor Q_1 off. This phenomenon may be appreciated by assuming that the transistor Q_1 is turned on by, let us say, an increase in base voltage from just below the firing point to just above the firing point. When this occurs, the collector of the transistor Q_1 drops in potential because of the increased current flow through the transistor Q_1 and, correspondingly, the base potential on a transistor Q_2 decreases a proportional amount. In addition, once the transistor Q_1 has been turned on, its emitter will be at substantially the same potential as its base and, since the emitters of the transistors Q_1 and Q_2 are tied together, the emitter of the transistor Q_2 will follow the emitter of the transistor Q_1 and go more positive. Thus the base of the transistor Q_2 will, on the switching action, drop a number of volts negative and the emitter of the transistor Q_2 will rise a number of volts so that the transistor Q_2 will be turned hard off. In this fashion, a very small increment in trans-

sistor Q_1 base voltage from just below its triggering point to just above its triggering point will result in a great change in base to emitter voltage in the transistor Q_2 . Accordingly, a small drop in the base voltage on the transistor Q_1 from just above its firing point to the voltage that it had just before it fired will not suffice to turn on the transistor Q_2 nor turn off the transistor Q_1 . Thus the base voltage on the transistor Q_1 must drop well below its "on" firing point in order to cause the reverse triggering. This difference between the triggering voltage necessary on the ascending slope of an input signal E_s and the descending slope of an input signal E_s has been called hysteresis.

It is this hysteresis which produces stability in the Schmitt trigger since it assures that a switch once it starts will continue. The hysteresis is also a concomitant of the fast switching.

The invention

20 FIG. 2 is an embodiment of this invention and specifically illustrates an improvement on the prior art Schmitt trigger which will permit setting the refire point at the same voltage level as the firing point while retaining the benefit of the hysteresis.

25 FIG. 2 illustrates a symmetrically firing Schmitt trigger which fires on the ascending slope of the input signal E_s in exactly the same fashion as does the prior art trigger illustrated in FIG. 1. However, once it has fired, so that the transistor Q_1 is on (and the transistor Q_2 is off) a current is pumped through the resistor R_6 in such a direction and magnitude so as to change the potential on the base of the transistor Q_2 in a direction and to an extent sufficient to cause the transistor Q_2 to refire once the input signal has decreased to a magnitude substantially equal to the triggering voltage. This result is achieved by use of the current source Q_3 .

30 Before describing the operation of the current source Q_3 , it should be noted that the single Q_1 collector resistor R_{34} of the prior art design has been split into two resistors R_3 and R_4 so that the base of the current source Q_3 may be connected between the resistor R_3 and the resistor R_4 . In this fashion the voltage magnitude on the base of the current source Q_3 will change proportionately with the voltage changes on the collector of the transistor Q_1 . In addition, the Q_2 base resistor R_{67} of the prior art is split into two resistors R_6 and R_7 so that the collector of the current source Q_3 can be connected, as shown, between these two resistors R_6 and R_7 . In this fashion, the voltage on the base of the transistor Q_2 will be modified as a partial function of the magnitude of the current that is supplied by the current source Q_3 .

35 It should be noted that the current source Q_3 in the embodiment shown is a PNP transistor. Accordingly, Q_3 will tend to be turned on by a drop in its base bias. The circuit is designed so that an appropriate drop does occur when the collector Q_1 drops as Q_1 is turned on. The base bias drop in Q_3 turns on Q_3 so that a current will flow through Q_3 and the resistor R_6 . The consequent current flow in the resistor R_6 raises the base bias on this NPN transistor Q_2 to a point where the transistor Q_2 can be more readily turned on than just prior to the Q_3 current flow. The triggering voltage as the input signal E_s descends can thus be set to be equal to the triggering voltage when E_s increases so that the result is a symmetrically firing Schmitt trigger.

40 The switching action between Q_1 and Q_2 occurs very much more rapidly than the turning on the transistor Q_3 . As a consequence, the increase in the bias on the base of the transistor Q_2 due to Q_3 current flow occurs after the bias on the base of Q_2 has been decreased by the switching action between the transistors Q_1 and Q_2 . If the time lag between the switching of the transistors Q_1 and Q_2 and the turning on of the current source Q_3 is not great enough, a capacitor C_6 may be added to increase the time lag sufficiently so that there will be no interruption with

the fast switching operation and so that the switching operation will not be rendered unstable.

The magnitudes of the resistors R_8 and R_9 are selected to control the magnitude of the current provided by the current source Q_3 .

Because of this increased current through the resistor R_6 , the base to emitter voltage of the transistor Q_2 is modified in such a fashion that the transistor Q_2 will turn on when the signal voltage E_s decreases to the desired switching voltage. It should be pointed out that this reverse switching occurs because as E_s decreases, the emitter of the transistor Q_1 also decreases since it is tied to the base of the transistor Q_1 when the transistor Q_1 is turned on. Since the emitter of Q_1 decreases, the emitter of Q_2 must also decrease, it being tied directly to the emitter of the transistor Q_1 . When the emitter of Q_2 decreases to the point such that there is sufficient forward bias on the transistor Q_2 , the transistor Q_2 will turn on. As Q_2 turns on, Q_1 turns off due to the decreased base voltage on Q_1 resulting from the decreasing input signal E_s and due to the increasing emitter voltage resulting from an increased current through the common emitter resistor R_5 . The turning off of the transistor Q_1 concurrently causes a decrease in current through the collector resistors R_3 and R_4 so that the collector of the transistor Q_1 rises, resulting in an increase in the base voltage of the transistor Q_2 . This feedback turns the transistor Q_2 on even harder so that a bistable switching operation occurs. Concurrently, the decrease in current through the collector resistors R_3 and R_4 causes an increase in bias voltage on the PNP transistor Q_3 so that the current source Q_3 tends to turn off resulting in a decrease in the current through the resistor R_6 . This decrease in current through the resistor R_6 returns the base voltage of the transistor Q_2 to its original value so that there will be repeatable switching when the input signal E_s starts to rise again.

From the above description it should be clear that in brief terms this invention involves the provision of a current source whose magnitude is responsive to the collector voltage on the transistor Q_1 and this current will be used to modify the base voltage on the transistor Q_2 . A current source having these characteristics and operating (in response to changes in the collector voltage on the transistor Q_1) at a slower rate than the switching rate will provide the change in transistor Q_2 base voltage necessary to compensate for the hysteresis and yet will not cancel out the hysteresis while switching takes place. Thus this invention retains the advantages of having hysteresis during switching and compensating for the effect of hysteresis during refiring.

The above description is of one particular embodiment of this invention. It would be apparent to those skilled in this art to make such modifications as would be necessary to adapt this invention to valves other than the NPN transistors Q_1 and Q_2 illustrated. Thus, PNP transistors could be employed with the appropriate change in voltage signs. It would also be possible to apply this invention to a Schmitt trigger employing electron tubes. Accordingly, it is intended in the claims to cover all such modifications as would fall within the scope of the invention.

For example, the major intended use of the invention is to design a symmetrically firing Schmitt trigger. However, there is no reason why the invention should be limited to those applications where the refiring point must be the same as the firing point. In effect, this invention provides a technique whereby the amount of hysteresis can be controlled by the design explained herein. The amount of hysteresis compensation can be designed to be any predetermined magnitude. Where designed for a symmetrically firing Schmitt trigger, the compensation is sufficient to equal the hysteresis and thus cancel out its net effect on refire voltage. In other applications differing amounts of compensation can be used so as to set the refiring point at any level.

The amount of hysteresis compensation supplied can be

sufficiently great so as to reverse the relative voltage levels between the fire and refire points. For example, in the embodiment illustrated, the refire point is at a lower voltage level than the firing point. By means of this invention, the hysteresis could be so over-compensated that the refire point would be at a higher voltage than the firing point. This over-compensation of hysteresis would not otherwise affect the operation of the switch in that the switch would still fire on a rising signal and refire on a falling signal.

This ability to change the relative voltage levels of the fire and refire point is unique with this invention and cannot be achieved with the hysteresis compensation techniques employed in prior art Schmitt triggers.

In addition to the particular type of design illustrated above in which a signal is supplied that tends to cancel hysteresis and that, by the proper selection of parameters, either reduces hysteresis, cancels the hysteresis or over-compensates for the hysteresis, it is possible to supply a signal which will tend to add to the hysteresis already present. Thus it is within the ambit of this invention to supply a bias to the control signal of the second valve (that is to the base of the transistor Q_2 in this embodiment) which will add to, as contrasted with compensate for, the hysteresis otherwise developed by the switching design.

The switch illustrated is one which fires on a rising input signal and refires on a declining input signal. However, a switch can readily be designed to fire on a declining input signal and refire on a rising input signal and the teachings of this invention can be applied to such a switch to cause a modification in the hysteresis inherent in that switch design.

Concerning terminology in the following claims, it should be understood that the use of the term function to relate parameters refers to partial function as well as complete function. Thus the bias on the transistor Q_2 is a function of the state of the transistor Q_1 because the state of Q_1 does affect that bias even though other factors such as the bus bar voltage levels, the magnitudes of the resistors R_6 and R_7 , and the current output from the transistor Q_3 also affect the base bias on Q_2 . Accordingly, the base bias on Q_2 is only a partial function of the state of Q_1 yet, herein, it is to be understood that the term function includes partial function.

The embodiment described in detail above broadly involves a control means Q_3 which responds to the state of the transistor Q_1 to modify the bias on the transistor Q_2 . The control means could just as well be designed to sense the state of the transistor Q_2 in order to modify the bias on the transistor Q_1 and in that fashion to modify the hysteresis of the overall switching device. After all, this is a bistable device and the modification of the bias on either of the switching elements would have comparable results. It is to be understood, herein, that a reference to a first valve and a second valve in the claims is strictly for the purpose of subsequent reference within each claim and the phrase "first valve," in general, refers to whichever valve is the one whose state is sensed by the control means. The fact that the transistor Q_1 is the valve at the input to the circuit does not mean for the purpose of this application and its claims that it is necessarily a "first valve."

What is claimed is:

1. In a bistable switching circuit having a first valve and a second valve, each of said valves having a first state and a second state and being interconnected such that said circuit has a first stable state and a second stable state, each of said valves having a control element and a low impedance output element, the low impedance elements of said valves being coupled to one another and having a common resistor, said circuit including an input lead connected to the control element of said first valve so that an input signal passing a first threshold voltage in a first direction will fire said circuit into its first state

and an input signal passing a second threshold voltage in a second direction will refire said circuit into its second state, the improvement comprising:

a voltage dividing bias means coupled to the control element of said second valve, and
control means responsive to said second state of said circuit to provide a control signal when said circuit is in said second state, said control signal being coupled to a point on said voltage dividing bias means to modify the bias on said control element of said second valve during said second state of said circuit.

2. The bistable switching circuit improvement of claim 1 wherein said control means is a current source comprising a third valve having an off state and an on state, the output of said current source being coupled to said point on said voltage dividing bias means, the control element of said third valve being coupled to the output of said first valve so that the state of said first valve will determine the state of said third valve.

3. The bistable switching circuit of claim 1 wherein said voltage dividing bias means is a first and second resistor connected in series to said control element of said second valve, and wherein the juncture between said resistors is said point to which said control signal is coupled.

4. The bistable switching circuit improvement of claim 1 further characterized by:

time delay means connected to said point on said voltage dividing bias means to provide a predetermined time delay in the application of said control signal to said control element of said second valve.

5. In a bistable switching circuit having a first transistor and a second transistor, each of said transistors having base, collector and emitter electrodes, said emitter electrodes being coupled to one another and having a common emitter resistor, said transistors being coupled to one another to provide said circuit with a first stable state and a second stable state, said circuit including an input lead connected to said base of said first transistor so that a rising input signal passing a first threshold voltage will fire said circuit into said first stable state and a falling input signal passing a second threshold voltage will refire said trigger into said stable state, the improvement comprising:

a voltage dividing bias means coupled to said base of said second transistor, and

a current source responsive to said second state of said circuit to provide a control signal when said circuit is in said second state, said control signal being connected to a point on said voltage dividing bias means to modify the bias on said base of said second transistor during said second state of said circuit, whereby said bias on said base of said second transistor will have a first predetermined value when said circuit is in said first state and a second predetermined value when said circuit is in said second state.

6. The bistable switching circuit improvement of claim 5 wherein said current source is a third transistor having an off state and an on state, said third transistor having base, collector and emitter electrodes, said base electrode of said third transistor being coupled to said collector of said first transistor so that the state of said first transistor will determine the state of said third transistor, the current output of said third transistor being said control signal that is connected to said point on said bias means.

7. The bistable switching circuit of claim 5 wherein said voltage dividing bias means is a first resistor and a second resistor connected in series to said base of said second transistor, and wherein the juncture between said resistors is said point to which said control signal is connected.

8. The bistable switching circuit improvement of claim 7 further characterized by:

a capacitor connected across said second resistor to provide a predetermined time delay in the application of said control signal to said base of said second transistor.
